UNITED STATES PATENT OFFICE.

LOUIS VIALA, OF YONKERS, NEW YORK, ASSIGNOR TO THE BIGELOW CARPET COMPANY, OF MASSACHUSETTS.

DESIGN FOR A RUG.

SPECIFICATION forming part of Design No. 33,939, dated January 22, 1901.

Application filed December 31, 1900. Serial No. 41,747. Term of patent 3½ years.

To all whom it may concern:

Be it known that I, LOUIS VIALA, a citizen of the United States, and a resident of Yonkers, in the county of Westchester and State of New York, have invented a new and original Design for a Rug, of which the following is a specification.

My design as shown in the drawing consists in a new design for a rug.

10 The design is composed of a central portion and a border.

Upon a background ornamented with roccoco forms of scrollwork appears a central flower-picture consisting of a central bouquet of 15 flowers on a substantially plain background surrounded by a shield-like boundary of scroll-like forms and flowers, constituting, as it were, a frame for the flower-picture. Depending from this frame on all sides are 20 garlands or festoons of flowers. This entire central portion of the rug is surrounded by a wide border composed of a succession of shield-like forms of varying shape and size, with bold 25 boundary-lines of roccoco or scroll-like forms, said shield-like forms inclosing grouped ar-

rangements of flowers. The extreme outer edge of said border consists mainly of a substantially continuous boundary of conventional leaf-like forms.

The most distinctive features of my design 30 are the central framed flower-picture, with its pendent festoons or garlands upon a background, and a surrounding border composed of a succession of bold variously-shaped shield-like figures inclosing arrangements of 35 flower groups.

The drawing shows one-quarter of the design, the remaining three-quarters being in all respects facsimiles thereof.

What I claim as new, and desire to secure 40 by Letters Patent, is—

The design for a rug, substantially as shown and described.

In testimony whereof I have signed my name to this specification in the presence of 45 two subscribing witnesses.

LOUIS VIALA.
